CLAIM

The ornamental design for a pressurized air delivery console, as shown and described.

DESCRIPTION

FIG. 1 is a front perspective view of a pressurized air delivery console according to the first embodiment showing our new design;

FIG. 2 is a left side view thereof;

FIG. 3 is a right side view thereof;

FIG. 4 is a top view thereof;

FIG. 5 is a bottom view thereof;

FIG. 6 is a front view thereof;

FIG. 7 is a rear view thereof;

FIG. 8 is a reverse perspective view thereof;

FIG. 9 is a front perspective view of a pressurized air delivery console according to the second embodiment showing our new design;

FIG. 10 is a left side view thereof;

FIG. 11 is a right side view thereof;

FIG. 12 is a top view thereof;

FIG. 13 is a bottom view thereof;

FIG. 14 is a front view thereof;

FIG. 15 is a rear view thereof; and,

FIG. 16 is a reverse perspective view thereof.

The broken lines illustrate portions of the pressurized air delivery console that form no part of the claimed design. Stippling and line shading have been used in the drawings to indicate a contrast in appearance.
